(57) **CLAIM**

The ornamental design for a refrigerator air filter assembly,
as shown and described.

DESCRIPTION

FIG. 1 is a top-front perspective view of a refrigerator air filter assembly according to our design;

FIG. 2 is a front-right perspective view thereof;

FIG. 3 is a front view thereof;

FIG. 4 is a right cross-sectional reference view thereof taken
along the line 4-4 in FIG. 3; and,

FIG. 5 is a bottom cross-sectional reference view thereof
taken along the line 5-5 in FIG. 3.

The broken line showing of portions of the article form no
part of the claimed design, and the broken line showing of
the refrigerator shows environment that is similarly
unclaimed.

Dash-dot lines adjacent un-shaded areas represent bounds of
the claimed design and form no part of the claimed design
themselves.

Stipple-filled portions of the article indicate a contrasting
appearance due to such portions being illuminated by inci-
dent light and does not indicate a stipple pattern in the
lighting itself.

FIGS. 4 and 5 are sectional views for purposes of illustrating
relationships between certain structures relative the front
vertical plane of the assembly.
